F. A. WALLOCH

COMBINED HOT AIR SCREEN AND DEFLECTOR

Filed July 8 1926

INVENTOR:

Frank A. Walloch

BY

Pierre James

ATTORNEY

UNITED STATES PATENT OFFICE.

FRANK A. WALLOCH, OF SEATTLE, WASHINGTON.

COMBINED HOT-AIR SCREEN AND DEFLECTOR.

Application filed July 8, 1926. Serial No. 121,158.

This invention relates to a combined air screen and deflector and more particularly to a device of this character which is designed to be utilized in connection with a register of a hot-air heating system.

An object of the invention is to provide a device, adapted to be applied to the wall of a room above a hot-air register, which will serve to screen hot air passing through the device of dust or solid particles of smoke so as to purify the heating medium and safeguard the room wall above the register from becoming discolored.

Another object is to provide a hot air screening device which will deflect a current of hot air from the room wall in a manner to most effectually utilize the hot air for warming the room.

A further object is to provide a screening device wherein the screen proper may be readily removed for cleaning the same.

A still further object is to provide a device for attaining the purposes above referred to, which is of simple and durable construction, inexpensive to manufacture and of an attractive appearance.

The advantages of the invention will be noted from the following description.

The invention consists in the novel construction, adaptation, and combination of parts hereinafter described and claimed.

In the accompanying drawing,—

Figure 1 is a view in transverse vertical section illustrating an embodiment of my invention shown applied; Fig. 2 is a front elevation of the device shown detached, the frame members being arranged as they are shown in Fig. 1; Fig. 3 is a view similar to Fig. 2, with the frame parts in their relatively open positions, the screen element being omitted from this view; and Fig. 4 is a fragmentary perspective view of Fig. 3.

In Fig. 1, the reference numeral 5 represents the wall having an opening for the frame 6 of a register 7. Provided within the frame 6 is a plate 7¹, conventionally known as the "register valve", normally occupying the position in which it is represented in the view. Thus arranged, said valve causes the hot air escaping from the duct 8 to be delivered into the room in a general

upwardly direction, as indicated by the arrow A.

The above referred to parts are or may be of any known or suitable construction and arrangement.

According to the present invention I provide two frames, indicated generally by 9 and 10 in Figs. 3 and 4. The frame 9, hereinafter designated as the bracket frame, is constructed of companion end elements; each of which being, preferably of an angle shape in transverse section to provide a flange 12 which is disposed in a vertical plane, and a flange 13 extending laterally from the inner side of the flange 12 with respect to the frame as a whole. Each of said bracket elements is formed to provide the lateral flange 13 with a plane vertical lower portion 13¹ and an upper portion of an arcuate shape substantially as shown in Figs. 1 and 4.

Said companion elements are connected together in spaced apart relation by means of transversely arranged rods 14 whose ends are rigidly secured, as by welding or otherwise, to the flanges 13 of the companion elements.

The spacing apart of the companion elements of the bracket frame is such that the flange parts 13¹ thereof may be interposed between the room wall 5 and the flange of the register frame, the wall fastenings (not shown) of the register frame serving to hold the bracket frame in place.

The second frame 10, hereinafter designated as the grille, consists of two side bars 15 which are curved to an arcuate shape and held in spaced apart parallel relation with each other by being welded or otherwise rigidly secured to the ends of spaced apart transverse rods 16.

Said grille frame is of a width to be inserted between the vertical flanges 12 of the bracket frame 9 and has its lower end pivotally connected to the flanges 12 as by prolonging the endmost rod, denoted by 16¹, of the series of rods 16, to extend through bearing holes provided therefor in the flanges 12. Such pivotal connection between the bracket frame 9 and the grille 10 is disposed in proximity to the connection of the bracket

frame 9 to the register frame and, being thus arranged, permits the grille to be swung into the relatively open position in which it is represented in Fig. 4 and by dotted lines 5 10¹ in Fig. 1, or into the position in which it is represented in Fig. 2 and by full lines in Fig. 1.

The numeral 17 (Figs. 1 and 2) represents a piece of foraminous material, such as 10 cheese cloth for example, which constitutes the air strainer of the device. This strainer or screen is placed upon the grille 10 when the latter is in the open or lowered position in which it is shown in Fig. 3, or by dotted 15 lines in Fig. 1.

Being thus supported upon the grille, the screen is swung upwardly therewith into position to be clamped between the two frames 9 and 10, as illustrated, in Fig. 1. 20 Said frames are secured in such screen clamping relation by means of latches 18, herein shown as depending from one of the rod elements, as 14¹, of the bracket frame.

By supporting the screen upon the relatively movable grille frame permits the latter being lowered for removing the screen for laundering.

With the parts arranged in the relative position in which they are illustrated in Fig. 30 1, the operation of the device is such that hot air currents escaping from the register ascend, as indicated by arrow A, against the under surface of the screen; part of the upper current of air passing through the foraminations thereof, the remaining part of the current being caused by the curved shape of the screen, acting as a deflector, to be delivered in a practically horizontal direction into the room, which is most efficient for room heating purposes. In such travel of the hot air currents through and against the under surface of the screen, particles of dust and other solids are carried by the air are enmeshed in the screen fabric, thereby purifying the air 40 and eliminating the main cause of that objectionable discoloration of a wall surface so frequently noticeable above a register. In such action, the flanges 12 of the bracket frame serve as side walls to prevent the 45 escape of the hot air currents laterally from either side of the device.

It is to be noted that the curvature, see Fig. 1, of that portion of the device in which the screen is applied is of substantially the 55 shape of a one-fourth of a circular circumference, a form which has proved very satisfactory for guiding the hot air stream from the register in a general upward and outward direction as it traverses the screen surface.

The screen may be composed of one or more plys or thicknesses of close mesh material, where cheese-cloth of commerce is employed, two plys thereof is found to be suitable under ordinary conditions.

The construction and operation of the invention will, it is believed, be understood from the foregoing description.

What I claim, is,—

1. In an air-screening device, a frame 70 having rigid side elements adapted to be secured to the wall of a room to have the frame extend therefrom in an upwardly inclined direction, a second frame hingedly connected to the first named frame, and releasable means engaging said frame for supporting the second named frame in position to hold a sheet of screening material against the under side of the first named frame.

2. In a hot-air screening device, a frame 80 having a curved upper portion located between two plane side wall portions, and lower portions adapted to be secured by means of the frame of a hot-air register to the surface of a room wall, a second frame 85 having a curvature corresponding to that of the curved portion of the first named frame and of a length to enter the space between the side walls thereof, and means for releasably connecting the two frames together 90 for detachably clamping a sheet of screening material against the curved portion of the first named frame.

3. A device of the character described, comprising a curved bracket frame adapted 95 to be secured to the wall of a room, said frame being composed of end elements and transverse elements disposed in spaced apart relations, a grille composed of curved end elements and substantially straight transverse elements disposed in spaced apart relations, said grille being pivotally connected at one edge thereof to the bracket frame, latch devices for releasably securing the grille to the bracket frame, and a sheet of 100 air-screening material adapted to be clamped between the transverse elements of the said frame and grille, respectively.

4. A device of the character described, comprising a bracket frame formed of 110 curved end elements, each of which is provided with a flange disposed in a substantially vertical plane and a second flange extending laterally therefrom, and rods rigidly secured at their ends to the lateral flanges 115 of said end elements to retain the latter in spaced apart relation, a grille frame formed of curved end elements and rods which are rigidly secured at their ends to the respective end elements, one of the last named rods 120 serving to pivotally connect the two frames together, a screen member removably placed upon the grille frame, and means for releasably securing the grille frame to the bracket frame in position to clamp the screen 125 in operative relation between both of the frames.

5. In a hot air screening device, the combination of a bracket frame adapted to be attached to the wall of a room to protrude 130

as a curve in an upwardly inclined direction therefrom, said frame having flanged end elements, a curved grille frame connected for relative movement to the bracket frame and adapted to be employed in the space between the flanges of said end elements for holding a sheet of screening material against the concave under surface of the bracket frame, and means for releasably securing the grille frame in its sheet holding relation to the bracket frame.

6. In a device of the character described, a pair of complementary frames hingedly connected together at their rear portions, one of said frames having plane lower portions

adapted to be secured to the wall surface of a room, the upper portion of such frame and the other frame being curved to afford there-
to convex upper surfaces and concave lower
surfaces and arranged to project outwardly 20
from said wall surface, and means for re-
leasably retaining the front portions of the
two frames in closed relation with each
other, the convex surface of the lower frame
serving to retain a sheet of screening mate-
rial against the concave surface of the upper
frame. 25

Signed at Seattle, Washington, this 29th day of May, 1926.

FRANK A. WALLOCH.
